HANDLE ATTACHMENT FOR BRUSHES

Arthur La Barre, Akron, Ohio

Application May 27, 1949, Serial No. 95,750

1 Claim. (Cl. 306—6)

1

This invention relates to a handle attachment for brushes, mops and similar cleaning devices having a backing member.

In the past, handle attachments of this nature have required that the backing member of the brush be of a particular shape, or that the backing member be provided with special indentations and/or apertures for mounting the attachment. Certain of the known prior art devices have been further complicated and made expensive by the use of machined parts and springs.

It is an object of the present invention to provide a simple, self-contained, rotatably adjustable handle attachment of the character described, which can be easily attached to the usual backing member of substantially any standard brush, pad or mop without materially altering said backing member.

It is a further object of the invention to provide simple, effective, handle attaching means of the character described requiring no machined parts with the exception of standard bolts and screws.

These and other objects of the invention will be manifest from the following brief description and the accompanying drawings.

Of the accompanying drawings:

Figure 1 is a side view illustrating an attachment embodying the features of the invention, the same being shown secured to the backing member of a brush, and also showing in dotted lines the reversed position of the handle.

Figure 2 is a cross-section taken on the line 2—2 in Figure 1.

Figure 3 is a top plan view of the attachment, showing in dotted lines the position of the handle when partially rotated towards the reversed position.

Referring particularly to Figures 1 and 2 of the drawings there is illustrated a handle attachment, indicated generally at 10, embodying the features of the invention, the same being shown secured to a backing member 11 of a brush 12, for attaching thereto an elongated handle 13 to extend at a suitable inclination from the backing member.

The handle attachment 10 may include a base plate 14 of thin metal adapted to be secured to the backing member 11, by means of wood screws 15, 15, received through spaced apertures 16, 16 in the base plate. Plate 14 has formed therein intermediate the spaced apertures 16, a hollow protuberance 17 which projects upwardly of the top face of the backing member to provide a recess for full reception of a head 18a of a bolt 18 re-

ceived through an aperture in the protuberance and held in that position by securement of the plate to the backing member.

Superposed on plate 14 may be a handle mounting plate 19 having a hollow conical protuberance 20 which complementally engages over the protuberance 17 having a square aperture therein for reception of a squared portion of a carriage bolt 18 therethrough (see Figure 2). Two relatively small indentations 28, 28 in plate 19 provide recesses for snug reception of the heads of said securing screws 15 which, when the plates 14 and 19 are clamped together by turning wing nut 22 on the outwardly projecting end of threaded bolt 18, prevent rotation of the plate 19 relatively of plate 14.

Integral with plate 19 and extending at approximately 45° to the plane thereof is a tubular extension 23 adapted to receive the end of the handle 13, the same being secured in place as by a screw 24.

The attachment is adapted to be sold or supplied as a self-contained unit including the base plate 14 and handle-mounting plate 19 clamped thereto by means of bolt 18 and nut 22, in which instance the two screws 15 may also be supplied with the unit with the heads 15a thereof engaged between said plates, as shown in Figure 2.

In use of the unit to attach the handle 13 to a scrub brush 12, for example, the wing nut 22 is loosened to permit turning handle plate 19 with respect to plate 14, as indicated in chain-dotted lines in Figure 3, to allow securing base plate 14 to the usual wood backing member 11 of the brush by means of the screws 15. When this is done the plate 19 is turned until the small indented portions 28 are aligned with the screw heads 15a and then the wing nut 22 is turned to clamp the plates 14 and 19 together in the manner previously described. The attached unit is then ready for insertion of a handle in the tubular extension 23.

With continued use of the brush 12 with the handle 13 in one position the bristles of the brush will tend to wear down to one side of the brush. When this wear occurs the wing nut 22 may be loosened sufficiently to disengage the screw heads 15a from the indented portions 28, thereby to permit rotation of plate 19 through 180°, until the screw heads become engaged in corresponding indentations 28, and then the wing nut 22 is turned to clamp plate 19 non-rotatably to base plate 14. In this manner, the brush is conditioned for additional wear.

Although the improved handle attaching de-

vice has been described in detail with reference to a scrubbing brush, it is clear that it may be similarly secured to backing members of many other cleaning, polishing, or treating brushes or pads.

It will be readily seen that the improved attachment is particularly adapted to be economically produced by means of metal stamping methods.

Thus, has been provided an improved self-contained handle attaching device for brushes or the like, which accomplishes the stated objects of the invention.

Modifications of the invention may be resorted to without departing from the spirit of the invention or the scope of the appended claim.

What is claimed is:

A handle attachment for brushes or pads having a backing member, comprising a base plate having an upstanding hollow conical protuberance providing a recess in the underside of the plate said protuberance having an aperture in the wall thereof at the upper end of the same, a bolt received upwardly through the aperture of the protuberance and having a head received in said recess to be above the underside of the base plate, said plate having holes therein at opposite sides of said protuberance, screws inserted downwardly through said holes for fastening the base plate to a said backing member and having heads thereof protruding upwardly of the base plate, a

5 handle mounting plate superposed on said base plate and having a hollow conical protuberance complementary to said protuberance on said base plate and rotatable thereon, said mounting plate being apertured and said bolt being received therethrough, a nut on said upper end of said bolt for clamping said plates together, said handle mounting plate having upwardly depressed portions providing recesses for snug reception of the heads of the fastening screws when the base and mounting plates are clamped together, thereby preventing relative movement between said base and mounting plates, and 10 socket means on said mounting plate for securing a handle thereto.
